UNITED STATES PATENT OFFICE.

CONRAD FREUND, OF ST. PAUL, MINNESOTA.

TOE WEIGHT.

Application filed June 24, 1922. Serial No. 570,573.

To all whom it may concern:

Be it known that I, CONRAD FREUND, a citizen of the United States, residing at St. Paul, in the county of Ramsey and State of Minnesota, have invented a new and useful Improvement in Toe Weights, of which the following is a specification.

This invention relates to toe weights, and is particularly adapted for use on race horses where it is desired to add an additional weight to the foot or hoof of the horse, so as to more evenly balance the stride to prevent interference and cross firing, thereby assisting in increasing the speed of the horse.

The weight may be attached to the horse's hoof, either at the toe or the side, and is constructed with a novel means for holding the weight in place on the attaching plate. It is a feature to provide a holding means which prevents the weight from vibrating and working loose while in use, so that it is practically impossible to lose the weight, without tearing the whole plate completely off of the horse's hoof.

The invention further provides an attaching plate with holding means adapted to receive different size weights, as is customary in toe weights for horses, so that 1, 2, 3 and 4 ounce weights may be used if desired.

It is of primary importance in racing a horse, to provide a toe weight, if one is used, which will not become loose or be lost in a race, for should the horse need such means to balance his gait, the horse can not be depended on if the weight is lost on one foot and remains on the other. A further object of the invention is in a rigid shoulder at the top and bottom of the weight, on the attaching plate, which firmly holds the weight in place and takes the strain off of the spring catch which holds the weight to the plate.

In the drawings forming part of this specification:

Figure 1 is a front view of the toe weight, as it appears on the attaching plate;

Fig. 2 is a cross-section on the line 2—2 of Fig. 1;

Fig. 3 illustrates the front view of the attaching plate;

Fig. 4 is a side view of the toe weight and plate, illustrating a larger size weight secured thereto;

Fig. 5 is a back view of the weight;

Fig. 6 is a front view of an alternative form of the invention; and

Fig. 7 is a central cross-section on the line 7—7 of Fig. 6.

The toe weight A is adapted to be held by the attaching plate B firmly and securely to a horse's hoof, so that the weight is held rigidly in place, while the horse is in action. Naturally when a horse is in action, a good deal of strain is brought to bear on the holding plate and the means of securing the weight thereto, so that it is highly essential to provide a suitable weight holding means for locking the weight to the plate. It is just as essential that the weights be interchangeable on the same holding plate, so that a larger or smaller weight can be used, as desired, without removing the holding plate from the hoof.

Various toe weights have been designed and many required the changing of the holding plate when the weight was changed and this has been found to be detrimental, as the hoof becomes worn from changing and will not hold or provide sufficient holding means to prevent the weight from coming off of the hoof.

The attaching plate B is formed with a broad, thin, flat base portion 10, which is curved slightly to fit the hoof and has screw holes 11, which are countersunk into the surface to receive the heads of the screws, so that it can be firmly attached to the horse's hoof, directly above the shoe or at the edge of the hoof, where the wall of the same is thick enough to receive the attaching screws.

The plate B extends upward and is formed with a narrow tongue 12, having an opening 13 extending through the same, which is adapted to receive a wire loop of ordinary well-known construction, through which the holding strap of the quarter boot is passed. The wire loop which is used and secured to

the plate B through the opening 13, holds the strap of the quarter boot in place on the hoof and also performs the function of providing a holding means for the upper end 5 of the plate B, to assist in firmly holding the same to the horse's hoof when in action.

The attaching plate B is formed with a projecting boss 14 which is formed with a recess 15, in which the spring catch 16 is 10 positioned. The stem 17 of the catch extends through the recess 15, projecting above the boss 14, and a suitable pin 18 is passed through the stem and extends on either side of the same, to form engaging loops 19. 15 The pin 18 forms a stop which engages in the recesses 26 in the side of the boss, and limits the downward movement of the spring catch 16. A coil spring 20, within the recess 15, holds the tongue 21 of the 20 catch normally in downward or engaging position.

The attaching plate B is formed with an opening 22 which is adapted to receive the tongue 23 formed on each of the weights A, 25 while the upper portion of the weight is engaged by the tongue 21 of the catch 16, which penetrates the recess 24 formed in the weight. When the weight A is attached to the plate B, the catch 16 engages in the recess 24, under the tension of the coil spring 20, so as to firmly and rigidly attach the weight to the plate. In this position, the weight approximately covers the heads of the screws in the openings 11 when the plate 30 is attached, so that they can not easily become disengaged from the hoof.

The pin 18 holds the spring catch 16 from rotation, by engaging in the notches 26 on either side of the boss 14 to hold the beveled 40 side of the tongue 21 in outward position as illustrated in Figs. 2 and 3. The weight A is attached to the plate by inserting the tongue 23 into the opening 22, and the upper edge of the weight pressed against the beveled surface of the tongue 21, forcing the same upward in the recess 15, and allowing the weight A to move into place. When the weight A is in place the catch 16 automatically snaps into the recess 24 and bears 45 with spring tension against the same, firmly and securely holding the weight A in position on the plate.

When it is desired to remove the weight A, the loops 19 can be readily engaged and the catch 16 raised sufficiently to release the tongue from the recess 24. The weights A are formed with a notch 25, adjacent the recess 24, which engages on either side of the lower end of the boss 14. The notch 25 and the tongue 23 eliminate any strain or side play from the catch 16, so that it is only necessary for the catch to hold the weight from forward or disengaging movement. This construction eliminates any unnecessary strain on the catch 16. The various

size weights are all made to readily fit the same holding plate B, making the weights interchangeable, which is more easily accomplished by means of the spring catch 16.

Figs. 6 and 7 illustrate an alternative 70 means for holding the weight A to the plate B. In this construction, in place of the spring catch 16, a set-screw 27 is threaded in and extends through the boss 14 in a manner to engage in the recess 24 of the weight 75 A, so that the inner end 28 of the set-screw engages firmly in the recess 24, to rigidly attach the weight to the holding plate.

In this construction, the weights A are exactly the same as used in Figs. 1 and 2 80 and can readily be interchanged by unscrewing the set-screw 27, far enough to disengage the end 28 from the recess 24.

Heretofore toe weights have been held to attaching plates by sliding the weights on a 85 beveled tongue and pounding them into tight frictional engagement with the tongue, so as to hold them in place; or a set-screw has been used to hold the weight. When held in this manner, they easily work loose and 90 come off or are lost, especially if the horse should strike a small rock. This invention has been designed to overcome this objection and to insure firm attachment of the weight while in action, or to allow the 95 weight to be easily removed. The boss 14 provides a shoulder at the top of the weight, and the tongue 23 a stop at the bottom. Thus the weight is held between these two points against the force of the pounding of 100 the horse's foot on the ground.

In accordance with the patent statutes, I have described the principles of my invention and the drawings show a form of the same, but I desire to have it understood that 105 this is only illustrative and that the invention can be carried out and applied to uses other than those set forth within the scope of the following claims.

I claim:

1. A toe weight for balancing a horse's hoof, including a hoof-engaging plate, a spring catch carried by said plate, and a weight adapted to be removably held by said catch to said plate.

2. A toe weight comprising a plate adapted to be secured to a hoof, having an opening therein at one end thereof, a boss formed on said plate at the other end, a weight having a hook adapted to engage within said opening and being formed with a notch adapted to straddle said boss, and means secured to said boss for latching said weight in place upon said plate.

3. A toe weight for balancing a horse's foot, comprising a plate adapted to be rigidly attached to the hoof, an opening formed in said plate, a spring catch carried by said plate, an interchangeable weight, an attaching tongue projecting from said weight 130

adapted to engage in said opening in said plate, and a recess in said weight adapted to be engaged by said spring catch, to secure said weight to said plate, against disengagement therefrom.

4. A toe weight including a plate adapted to be secured to a hoof, a spring catch carried by said plate, a recess formed in said

plate, an interchangeable weight, a tongue formed on said weight, and a recess opposite 10 said tongue, whereby when said tongue engages said recess, said spring catch is adapted to engage in the recess in said weight, to attach the same against free disengagement therefrom.

CONRAD FREUND.
